US00D504893S

(12) **United States Design Patent** (10) Patent No.: **US D504,893 S**
(45) Date of Patent: **** May 10, 2005**

(54) **DOCKING UNIT FOR AN ELECTRONIC COMPUTER**

(75) Inventor: **Satoshi Araki**, Suginami-ku (JP)

(73) Assignee: **Kabushiki Kaisha Toshiba** (JP)

(**) Term: **14 Years**

(21) Appl. No.: **29/194,930**

(22) Filed: **Dec. 4, 2003**

(30) **Foreign Application Priority Data**

Sep. 25, 2003 (JP) 2003-027907

(51) LOC (7) Cl. **14-02**

(52) U.S. Cl. **D14/434**

(58) Field of Search D14/432, 434;
361/679-87; 200/5 R, 5 A, 6 R, 6 A
